UNITED STATES PATENT OFFICE.

JOHN L. WERRBACH, OF CHICAGO, ILLINOIS.

TRAP FOR DRAIN-PIPES.

1,142,469.

Specification of Letters Patent.

Patented June 8, 1915.

Application filed March 31, 1913. Serial No. 757,851.

To all whom it may concern:

Be it known that I, JOHN L. WERRBACH, a citizen of the United States, residing at Chicago, in the county of Cook and State 5 of Illinois, have invented certain new and useful Improvements in Traps for Drain-Pipes, of which the following is a specification.

My invention relates to improvements in 10 traps for drain pipes, and it has for its salient object to provide means whereby the trap may be discharged of its water-seal with the utmost convenience, and the manipulation of the trap to empty it will effect 15 the mechanical sealing of the drain pipe.

Another object of the invention is to provide a construction which affords convenient access for freeing the trap of collected sediment or obstructing objects; and it is the 20 general object of the invention to provide a simple and improved trap of the character referred to.

To the above ends, the invention consists in the matters hereinafter described and 25 more particularly pointed out in the appended claims.

In the accompanying drawing, Figure 1 is a side elevation of a trap embodying my 30 invention; the parts being shown in normal position, *i. e.*, with the trap open to receive and permit the passage of waste water; and Fig. 2 is an edge elevation of the device shown in Fig. 1.

Referring to the drawings, 1 designates 35 the inflow pipe or receiving side of the trap, 2 the outflow pipe or discharge side of the trap, 3 the sealing and cleaning chamber, and 4 the siphon pipe which connects the sealing chamber with the discharge pipe. A 40 valve, designated as a whole 5, is inserted in the inflow pipe, said valve comprising a suitable valve-casing 6 set in as a section of the inflow pipe, and a plug valve 7 extending through the valve-casing and controlling the passage through the latter. The 45 valve 7 is a tapered, rotary valve provided with a through port, indicated in dotted lines at 8, which in the normal position of the valve permits the waste liquid to pass 50 freely, while in the other position of the valve the passage is sealed. To limit and determine the throw of the valve in each of its directions, a stud 9 is mounted on the valve-body, which cooperates with shoulders 55 10 and 11 formed upon the valve-casing

ninety degrees apart. The stem of the valve-body is provided with a lever handle 12 whereby the valve may be opened and closed; this handle preferably, and as shown, hanging vertically downward in its normal 60 position. With the lowermost part of the sealing chamber 3 is connected a by-pass pipe 13, which leads from said chamber downwardly and is attached to and communicates with a nipple 14 which leads into 65 the outflow pipe 2 of the trap. In the descending part of the by-pass pipe is interposed a valve, designated as a whole 15, comprising a casing 16 and a valve-plug 17; these parts being constructed and arranged 70 generally similar to the valve 5 hereinabove described, except that they are smaller.

Upon the stem of the valve-plug 17 is fixed an arm 18 which extends laterally in a plane parallel with the plane of movement 75 of the hand lever 12, and the end of the arm 18 is connected with said hand lever 12 by a link 19, so that the two valve-plugs are positively connected to move together. The port of the valve 15 is arranged at right 80 angles to the port of the valve 5, so that when in normal position the by-pass pipe is sealed. Upon the hand lever 12 being swung (to the left, as shown in the drawing) 85 into position to shut off the inflow pipe, the by-pass valve is opened and the liquid which normally forms the seal in the sealing chamber thus permitted to flow from the chamber into the pipe 2 leading from the discharge side of the trap. 90

In order to permit ready access to the bottom of the sealing chamber with a prod or wire, the connection between the descending and lateral parts of the by-pass pipe takes the form of a T-coupling 20, the lower 95 arm of which is closed by a removable screw-cap 21. Obviously, when this cap is removed and the valve 15 opened, a prod or wire may be inserted upwardly so as to reach into the sealing chamber for the purpose of dislodging any obstruction therein. 100

The operation of the device has been sufficiently described. The device finds a valuable field of usefulness in those sections of the country where the plumbing is likely 105 to freeze in winter. By simply shifting the valve-controlling lever, the trap is instantly discharged and rendered immune to danger by freezing. At the same time, all danger from sewer gas is precluded because the 110

very act of opening the drain to empty the trap closes the inflow pipe, and thus precludes the escape of sewer gas.

While I have herein shown and described 5 a practical and preferred embodiment of the invention, yet it is to be understood that the details of construction and arrangement may be modified without departing from the invention.

10 I claim as my invention:

1. A trap having the usual inflow and discharge passages and interposed liquid seal chamber, in combination with a by-pass connection between the lower part of the 15 liquid seal chamber of the trap and the discharge passage thereof, a valve above the trap controlling the inflow passage, a valve controlling the by-pass connection, and operative connections between said valves 20 whereby they are made to move together, the one opening as the other closes, and vice versa.

2. A trap having the usual inflow and discharge passages and interposed liquid 25 seal chamber, in combination with a by-pass connection between the lower part of the liquid seal chamber of the trap and the discharge passage thereof, a rotary valve above the trap controlling the inflow pipe, a rotary valve controlling said by-pass and having its port arranged at right angles to the port of the first named valve, a handle operatively connected with one of said valves, and operative connections between said handle 30 and the other valves, whereby both valves are compelled to move together.

3. In a trap for drain-pipes, the combination 35 with the inflow pipe, the outflow pipe, the liquid seal-chamber, and the siphon connection between said chamber and the outflow pipe, of a rotary valve controlling the inflow pipe, a by-pass pipe connected with the lower part of the seal-chamber and leading thence to the outflow pipe, a rotary 40 valve controlling said by-pass pipe, a hand lever connected with one of said valves, an angularly-extending arm connected with 45

the other valve, and a link connecting said hand lever and arm, substantially as described.

4. The combination with a fluid receiving member of an inlet conduit therefor, a valve in said inlet conduit, an outlet conduit, a bypass interposed between said member and outlet conduit, a valve member in 50 said bypass having its port arranged at right angles to that of the first named valve and operative connections between said valves to move the same in unison, whereby the one valve is opened when the other 55 is closed.

5. A drain pipe consisting of upper and lower sections and a connecting trap, an angular bypass comprising one member leading downward from the lower part of 60 the trap and closed by a removable cap and a member connecting said first named member with the lower section of the pipe, a rotary valve controlling the upper section of the pipe, a rotary valve controlling the 65 bypass and having its port at right angles to the first named valve, a handle for operating one of said valves, and means connecting said valves to move them in unison.

6. A drain pipe consisting of upper and 70 lower sections and a connecting trap, an angular bypass comprising one member leading downward from the lower part of the trap and closed by a removable cap and a member connecting said first named member 75 with the lower section of the pipe, a rotary valve controlling the upper section of the pipe, a rotary valve controlling the bypass and having its port at right angles to the first named valve, a handle for operating one of said valves, means connecting 80 said valves to move them in unison, and means to limit the rotation of the valves to a quarter turn.

JOHN L. WERRBACH.
